CLAIM

The ornamental design for a cuticle remover, as shown and described.

DESCRIPTION

FIG. 1 is a front elevational view of a cuticle remover, showing my new design;

FIG. 2 is a top plan view thereof;

FIG. 3 is a right side elevational view thereof, the left side being substantially a mirror image thereof;

FIG. 4 is a left side elevational view thereof;

FIG. 5 is a rear elevational view; and,

FIG. 6 is a bottom plan view thereof.
